UNITED STATES PATENT OFFICE.

DATUS C. SMITH, OF NEW YORK, N. Y.

DESIGN FOR A BARBED FENCE-WIRE.

SPECIFICATION forming part of Design No. 34,833, dated July 23, 1901.

Application filed June 21, 1901. Serial No. 65,508. Term of patent 14 years.

To all whom it may concern:

Be it known that I, DATUS C. SMITH, a citizen of the United States, residing at New York, in the county of New York and State of New York, have invented and produced a new, useful, and original Design for a Barbed Fence-Wire; and I do hereby declare the following to be a full, clear, and exact description of the invention, such as will enable others skilled in the art to which it appertains to make and use the same.

In the accompanying drawings, which are to be taken as a part of this specification, Figure 1 represents a plan view of a broken-away portion or section of a barbed fence-wire, showing my new design; and Fig. 2 is a side view of the same.

As shown in the drawings, the said barbed fence-wire consists of a single wire A, having at intervals therein crimps or bends, one of which is shown at B, and also having at intervals thereon barbs, one of which is denoted by the letter C, the said barbs having their intermediate portions appearing as bent or coiled around enlargements in the wire, so

as to leave prongs projecting in opposite directions therefrom, said enlargements being formed so as to present a flattened appearance or surface *a*, with lateral swells or protuberances *b*, which are embraced by the barbs. 30

As will be seen, the leading or material features of my design reside in a single wire having at intervals crimps or bends therein and also having at intervals barbs thereon, appearing as bent or coiled at their intermediate 35 portions around enlargements in the wire, so as to leave prongs projecting in opposite directions.

Having thus described my invention, what I claim as new, and desire to secure by Letters 40 Patent of the United States, is—

The design for a barbed fence-wire, substantially as herein shown and described.

In testimony whereof I affix my signature in presence of two witnesses.

DATUS C. SMITH.
